UNITED STATES PATENT OFFICE.

JOHN GREENHOUSE, OF CAMBRIDGE SPRINGS, PENNSYLVANIA.

CURTAIN-HOLDER.

1,089,049.

Specification of Letters Patent.

Patented Mar. 3, 1914.

Application filed July 3, 1913. Serial No. 777,165.

To all whom it may concern:

Be it known that I, JOHN GREENHOUSE, a citizen of the United States, residing at Cambridge Springs, in the county of Crawford and State of Pennsylvania, have invented certain new and useful Improvements in Curtain-Holders; and I do hereby declare the following to be a full, clear, and exact description of the invention, such as will enable others skilled in the art to which it appertains to make and use the same.

This invention relates to holders for curtains and roller shades used in connection with the windows of dwelling houses; and it consists in the novel construction and combination of the parts hereinafter fully described and claimed whereby the curtains are supported at various levels and whereby the ventilation of the room is assured.

In the drawings, Figure 1 is a front view of a window provided with a curtain holder according to this invention. Fig. 2 is a vertical section, taken on the line $x-x$ in Fig. 1. Fig. 3 is an end view of one of the brackets and a portion of the curtain bar, and is drawn to a larger scale. Fig. 4 is a plan view of the same. Fig. 5 is a cross-section through the curtain bar, taken on the line $y-y$ in Fig. 4. Fig. 6 is a detail plan view of one end portion of the air deflecting plate, showing portions of the bracket and curtain bar in section. Fig. 7 is a detail view of one of the fastening pins. Fig. 8 is a cross-section through one of the guides, taken on the line $z-z$ in Fig. 1. Fig. 9 is a longitudinal section through a portion of one of the guides, taken on the line $w-w$ in Fig. 8.

The window frame 2 is provided with two slidable window sashes 3 of any approved construction. Vertical guides 4 are secured to the window frame, one at each side of the window opening. These guides 4 are formed of thin sheet metal, and they have flanges 5 at their side edges which form a channel down the front portion of each guide.

The flanges 5 preferably project outwardly, clear of the window frame, but they may be constructed to project in any convenient way. The back of each guide is indented or stamped so as to form a series of ratchet-shaped teeth 6. These teeth are formed without perforating the sheet metal, and they form recesses 7 at the back of each guide, and they extend laterally across the channel of the guide.

Slides 8 of thin sheet metal are provided

and have flanges 9 at their edges which straddle the flanges 5 of the guides 4. Spring pawls 10 are secured to the slides 8, and work in the channels of the guides and engage with the teeth 6. These pawls 10 project below the edges of the slides, and have handles or buttons 11 for retracting them by hand.

Brackets 12 are secured to the upper end portions of the slides by means of flanges 13, and these brackets project upwardly. A roller 14 for a shade or curtain 15 is journaled in the brackets 12 and is of any approved construction, but this roller may be dispensed with if desired. Each bracket 12 has a slot 16 in its upper part, and has also an eye 17 at its top. The bracket is preferably formed of sheet metal, and the eye is formed by bending the sheet metal above the slot 16 which is substantially horizontal.

A channel-shaped bar 18 is provided for supporting the curtain 19, a portion only of which is shown, and the curtain is formed of any convenient material, such as muslin, and it is connected to the curtain bar in any approved manner. The curtain is preferably formed of two similar sections so that it can be draped at the sides of the window. Curved arms 20 are provided at the ends of the curtain bar, and the curtain bar is formed of telescopic sections so that it can be lengthened or shortened to suit windows of different width, and so that it can be secured firmly in place against the brackets. The curved arms 20 have lugs or plates 21 at their ends, which have slots 22 which register with the slots 16 of the brackets when the lugs 21 abut against the flanges 13 and the eye 17 of the brackets.

An air deflector plate 24 is provided, and its end portions 25 are slidable in the slots 22 and 16. The rear part 26 of the air deflector plate is offset downwardly and projects into the proximity of the upper window sash, and it preferably projects into the path of the lower window sash. The front part 27 of the air deflector plate projects upwardly and extends over the curtain bar. The front edge of the air deflector plate preferably has a downwardly projecting flange 28 and a bead 29 which stiffen it and which make a neat appearance, and the flange 28 also prevents much dust from settling on the top portion of the curtain. Each end portion 25 of the air deflector plate has a shoulder 30 which bears against the bracket 12 adjacent

to it, and has also a shoulder 31 for the lug 21 to bear against. Each end portion 25 also has two holes 32 and 33. The inner hole 32 registers with the eye 17, and the outer hole 33 comes outside the lug 21.

5 Forked spring pins 34 are provided at each end of the air deflector plate, and secure the curtain bar and the deflector plate to the brackets 12. Each pin 34 has a long 10 straight end portion 35 which passes through an eye 17 and a hole 32. The other end portion 36 of the pin is shorter than the end portion 35, and has an offset portion 37 at its lower part. This offset portion 37 is 15 inclined away from the part 35, and it is pressed toward the part 35 and is then thrust through the hole 33 so that the lug 21 is pressed against the eye 17 and is held securely in place by the resilience of the 20 spring pin. The telescopic formation of the curtain bar permits the lugs 21 to be pressed against the eyes 17 by the spring pins.

The slides can be set at any desired level, 25 so that the upper sash of the window can be opened and the air from outside the dwelling deflected upwardly into the room so that the room is well ventilated and no draft is formed. When the air deflector 30 plate is lowered onto the lower sash it either locks it or prevents it from being raised without making considerable noise, and thus in a measure protects the house from burglars. When the lower sash is raised with 35 sufficient force to raise the air deflector plate, the pawls make considerable noise as they slide over the ratchet teeth without being first retracted by hand. The air deflector plate can be set for the admission of 40 any desired amount of air, and for the egress of foul air from the room, without injury to the curtain, and it thus provides for the sanitary ventilation of the room. The curtain 19 can be removed and replaced as often 45 as desired by merely lifting down the curtain bar after pulling out the spring pins, and the slides can be operated from the floor without the use of a step ladder by retracting the pawls and subsequently using them 50 as handles to raise or lower the slides.

What I claim is:

1. The combination, with a window frame, of supporting brackets carried by the window frame, a curtain support carried by 55 the said brackets, and an air deflecting plate attached to the said brackets and extending rearwardly between the sides of the window frame and forwardly and upwardly over the curtain support.
- 60 2. The combination, with a window frame, and upper and lower window sashes slidable in it; of supporting brackets carried by the window frame, a curtain support carried by the said brackets, and an air deflecting plate 65 attached to the said brackets and extending

rearwardly between the sides of the window frame into the path of the lower window sash and extending forwardly and upwardly over the curtain support.

3. The combination, with a window frame, 70 of supporting brackets carried by the window frame, a curtain support carried by the said brackets, and an air deflecting plate attached to the said brackets and extending rearwardly between the sides of the window frame and forwardly and upwardly over the curtain support, 75 said plate having a downwardly projecting beaded flange at its front edge.

4. The combination, with a window frame, 80 of a vertically adjustable curtain support carried by the window frame, and an air deflecting plate which slides up and down with the curtain support and which extends over it and between the sides of the window frame and which operates to deflect the incoming air upwardly.

5. The combination, with a window frame, 85 of supporting brackets carried by the window frame and provided with slots, a curtain support carried by the said brackets, and an air deflecting plate provided with 90 end portions which engage slidably with the said slots, said plate extending rearwardly between the sides of the window frame and forwardly and upwardly over the curtain support.

6. The combination, with a window frame, 95 of vertical guides secured to the window frame, vertically adjustable brackets carried by the said guides and provided with 100 slots, a curtain bar provided at its ends with arms and lugs having slots which register with the said slots, an air deflecting plate 105 the end portions of which engage slidably with the registering slots, said plate extending over the curtain bar, and means for securing the said plate and curtain bar to the brackets.

7. The combination, with a window frame, 110 of supporting brackets carried by the window frame and provided with slots and eyes, a curtain bar provided at its ends with arms and lugs having slots which register with the said slots, said lugs being movable laterally into and out of engagement with the brackets, an air deflecting plate the end portions of which engage slidably with the registering slots, said plate extending over the curtain bar, and fastening devices which 115 clamp the said lugs against the brackets.

8. The combination, with a window frame, 120 of supporting brackets carried by the window frame and provided with slots and eyes, a curtain bar provided at its ends with arms and lugs having slots which register with the said slots, said lugs being movable laterally into and out of engagement with the brackets, an air deflecting plate the end portions of which engage slidably with the reg- 125

istering slots, said plate having also pin holes and retaining shoulders and extending over the curtain bar, and forked spring pins which engage with the brackets and with the holes in the air deflecting plate and which secure the said plate and curtain bar to the brackets.

9. The combination, with stationary supporting guides, each guide being formed of thin sheet metal and having flanges at its edges which form a channel, each guide having also an imperforate back and a series of teeth pressed up from its back, said teeth

projecting forwardly in the channel and forming recesses at the back of the guide, 15 slides provided with flanges at their edges which overlap the flanges of the guides, catches connected to the slides and engaging with the teeth of the guides, and a curtain support carried by the said slides. 20

In testimony whereof I have affixed my signature in the presence of two witnesses.

JOHN GREENHOUSE.
